RESILIENT ABRASIVE BLANKET

Claude B. Schneible, Chicago, Ill.

Application October 27, 1937, Serial No. 171,389

3 Claims. (Cl. 51—8)

This invention relates to a resilient abrasive blanket or stop. The invention may obviously, however, be applicable to other uses.

An object of the invention is to provide a resilient blanket or stop of simple construction which can be securely anchored to a wall or supporting plate, the resiliency of the blanket being increased by the specific conformation of the rear side of the blanket. A further object 10 is to provide a resilient blanket of special construction by which the resiliency of the structure is increased and its resistance to wear by abrasive blasting considerably prolonged. Other specific objects and advantages will appear as the 15 specification proceeds.

The invention is illustrated in a preferred embodiment, by the accompanying drawing, in which—

Figure 1 is a broken plan view of the rear 20 side of the blanket or stop embodying my invention; Fig. 2, a transverse sectional view, the section being taken as indicated at line 2 of Fig. 1, the section also illustrating the metal plate to which the blanket is secured by rubber 25 rivets; Fig. 3, a transverse sectional view, the section being taken as indicated at line 3 of Fig. 1, the metal plate support being removed; and Fig. 4, a transverse sectional view similar 30 to Fig. 3 showing a modified form of the invention.

In sand and other abrasive blasting operations, it is found that the back stop plates or walls wear away rapidly under the force of the abrasive. A resilient wall is more effective than 35 metal, but tends after some time to wear under the constant application of the abrasive. I have found that the life of the resilient wall can be greatly increased and its resistance to the abrasive increased by forming the rear side of the 40 blanket with a number of spaced concavities which increase the elasticity or resiliency of the blanket. At the same time, I prefer to employ ridges between the concavities so that the blanket can be firmly anchored to a metal back 45 plate or other suitable support.

In the illustration given, the blanket A of rubber or other suitable resilient material is provided with a number of spaced concavities 10, the spaces between the concavities forming ridges 50 or plateaus 11. The concavities 10 are formed in the rear side 12 of the blanket, the front side 13 being preferably even.

In order to secure the blanket rigidly and firmly to a metal plate or the like forming the 55 rear wall for the blasting chamber, I provide

the ridges or plateaus 11 with rivet holes 14, the rivet holes extending about halfway through the blanket.

The modification shown in Fig. 4 is substantially the same as that already described except 5 that the blanket B is provided with spaced knobs or projections 15 instead of concavities.

In the use of the device, I apply the blanket to a wall or metal plate, as desired. When the blanket is in position, I form a slit in the front 10 of the blanket aligned with each of the holes 14 so as to be able to pass a screw or rivet or other suitable fastening device through the slit and the aligned hole 14. It will be observed 15 that with this construction, any suitable fastening means can be employed for passing through the slit and hole and into the retaining board 20 or plate or wall. As illustrated in Fig. 2, a metal plate provided with perforations aligned with the holes 14 may be employed and rubber rivets 14^a may be passed through the blanket and plate to secure the blanket to the plate as described more fully in my co-pending application, Serial No. 171,390 for Resilient rivet and 25 method of securing resilient blanket to support. Other securing means will, however, be found 30 satisfactory.

When the blanket is then supported upon a 35 wall or plate or board to provide the background for the abrasive operations, it is found that the blanket, yielding as it does under the influence of the thinner portions formed by the concavities, reflects the abrasive grains much more readily so that there is less tendency for the blanket to wear. The rivet holes 14 serve the double 40 function of increasing the flexibility of the ridge or plateau portions 11, while at the same time providing spaces for the rivets or other fastening means employed. The ridge or plateau portions 11 provide a firm regular surface for receiving the rivets or the like so as to provide a solid anchor against the plate, etc.

While in the foregoing description, I have set 45 forth one illustrative example of the invention, it will be understood that many changes in the details of construction may be made without departing from the spirit of my invention. The foregoing detailed description has been given for clearness of understanding only, and no unnecessary limitations should be understood therefrom, but the appended claims should be construed as broadly as permissible, in view of the prior art.

I claim:

1. An abrasive stop of the class set forth 55

- adapted to be applied to a rigid support, said stop comprising a resilient blanket having an even front surface and an even rear surface adapted to lie against the support and provided
- 5** with dished concavities, the areas between the concavities being provided with openings to provide attachment to said support and providing substantially non-yielding bases lying against said support.
- 10** 2. An abrasive stop of the class set forth adapted to be attached to a support, said stop comprising a resilient blanket having an even front surface and a rear surface even throughout except as to spaced circular concavities, the
- 15** even areas between said concavities providing substantially unyielding bases and areas for attachment to said support whereby each of said concavities is adapted to be suspended from said attachment means upon the support.
- 3.** An abrasive stop of the class set forth **5** adapted to be applied to a back support comprising a rubber blanket having an even front surface and a rear surface provided with spaced circular concavities with diamond-shaped plateaus therebetween, said plateaus having their **10** wide flat faces in a single plane abutting and adapted to be secured to the support and also being relatively non-flexible laterally.

CLAUDE B. SCHNEIBLE. **15**
